WASTE CONVEYORS

Lucien Péras, Billancourt, France, assignor to Régie Nationale des Usines Renault, Billancourt, France
Filed July 17, 1961, Ser. No. 125,057
Claims priority, application France July 22, 1960
1 Claim. (Cl. 198—174)

This invention relates to waste conveyor apparatus, that is, apparatus for collecting chips, borings, turnings and like cuttings from machine tools, and its specific object is to improve apparatus of this character with a view to increase their efficiency.

In hitherto known apparatus of this type a conveyor chain carrying waste driving members is reciprocated in a collector channel. This chain consists generally of a tube carrying the driving members which is guided on a solid or tubular core.

The improvements according to this invention consist essentially in substituting an angle iron for the tube guided on a core, the vertex of this angle iron being directed upwards and having welded thereon the vertical spurs or like elements and V-shaped members commonly used in apparatus of this type for carrying along the chips. Suitably spaced rollers carried by the bottom of the collector channel support the angle iron and constitute a slideway.

This embodiment of conveyor, characterized by its simplicity, has in particular the following advantages and use:

Very moderate wear of movable parts;

Extremely satisfactory tightness of these parts; and

The minute waste cannot interfere with the proper operation of the apparatus.

Referring to the attached drawing illustrating a typical embodiment of the improved waste conveyor of this invention:

FIGURE 1 is an elevational view of one fragment of the apparatus;

FIGURE 2 is a plane view from above of the same fragment, and

FIGURE 3 is a cross-section taken on a larger scale.

The structure shown notably in FIGS. 1 and 2 of the drawing comprises a reciprocating chain consisting essentially of one or a plurality of angle irons 1 suitably interconnected and so directed that the bisectrix of the angle

2

formed by their wings extends vertically, the angle irons being disposed in the waste collecting channel (not shown) so as to straddle the slideway carried by the bottom of this channel and constituted by suitably spaced rollers 2.

5 In FIG. 2 it will be seen that these rollers 2, in the specific form of embodiment shown by way of example, are each mounted in a supporting case 3 on a pin 4 through the medium of ball-bearing 5. From FIG. 3 it will also be seen that the outer periphery of each roller 10 is suitably shaped to conform to the inner contour of the bottom of the angle irons, between the wings thereof. The waste driving members, consisting in the usual manner of V-shaped members 6 associated with vertical spurs 7, are secured at proper longitudinal intervals on the angle irons 1, preferably by welding.

Of course, various modifications may be brought to the embodiment shown and described herein, without however departing from the spirit and scope of the invention as set forth in the appended claim.

20 I claim:

In a collector channel for waste scrap, a scrap conveyor chain consisting of a plurality of connected angle iron members opening downwardly and with their vertexes extending upwardly and their two sides extending downwardly and outwardly, transversely extending scrap drive push members consisting of V-shaped elements sloped rearwardly of the angle iron members and secured to said sides, and guide members in said collector channel comprising a plurality of laterally spaced aligned vertical rollers with a peripheral profile corresponding to the profile of the inner corner of said vertexes, said angle iron members being disposed with the surface of said inner corner in contact with the peripheral profile of said vertical rollers whereby scrap is driven by said conveyor 25 30 35 without scrap wedging between said angle iron members and rollers.
